To all whom it may concern:

Be it known that I, Emil I. Harman, a citizen
of the United States, residing in Philadelphia,
Philadelphia County, Pennsylvania, have invent-
ed a new, original, and ornamental Design for
a Phonograph Tone Arm Head, of which the fol-
lowing is a specification, reference being had to
the accompanying drawing, forming part thereof,
in which:

Fig. 1 is a perspective view of a phonograph
tone arm head showing my design;

Fig. 2 is a side elevational view thereof; and
Fig. 3 is a front elevational view thereof.

I claim:

The ornamental design for a phonograph tone
arm head, substantially as shown.

EMIL I. HARMAN.
